UNITED STATES PATENT OFFICE.

ROBERT F. HUDSON, OF RICHMOND, VIRGINIA, ASSIGNEE, BY DIRECT AND MESNE ASSIGNMENTS, TO GRAVITY RAILWAY SIGNAL COMPANY, INCORPORATED, OF RICHMOND, VIRGINIA.

RAILWAY-SIGNAL.

1,114,477.

Specification of Letters Patent. Patented Oct. 20, 1914.

Application filed August 4, 1910. Serial No. 575,476.

To all whom it may concern:

Be it known that I, ROBERT F. HUDSON, a citizen of the United States, residing at Richmond, in the county of Henrico and State of Virginia, have invented a new and useful Railway-Signal, of which the following is a specification.

This invention has reference to improvements in railway block signals and its object 10 is to provide a visible signal which shall normally remain at safety but by the entrance of a train into the block controlled by the signal the latter will move to the danger position and there remain until the train has 15 passed from the block, the system avoiding the use of conductors along the line of way other than the traffic rails. Furthermore the signal is returned to the safety position by the establishment of a closed electric circuit 20 so that on the establishment of conditions in the block which would be dangerous to an approaching train the signal will remain at the danger position until the dangerous conditions have been remedied.

25 The present invention will be best understood from a consideration of the following detailed description taken in connection with the accompanying drawings forming a part of this specification, in which drawings:—

30 Figure 1 is a side elevation of the structure designed to move the signal to the safety position but responsive to the passage of a train to move the signal to the danger position. Fig. 2 is a vertical cross section of the structure of Fig. 1 on the line A—B of Fig. 5 with some parts in elevation.

Fig. 3 is an elevation of the right hand side of the structure of Fig. 1. Fig. 4 is a section on the line C—D of Fig. 5 with some parts 40 omitted. Fig. 5 is a top plan view of the structure of Fig. 1. Fig. 6 is an elevation of a relay used in connection with the present invention. Fig. 7 is a plan view of a short section of track showing a semaphore or

45 target and a portion of the operating means therefor. Fig. 8 is a side elevation with parts in section of the structure of Fig. 7. Fig. 9 is a view of the upper end of the semaphore mast or post. Fig. 10 is a diagram 50 showing the electrical connections of two adjacent blocks. Fig. 11 is a detail view showing the rod 16 connected for operating the semaphore in the opposite direction to the

construction shown in Fig. 9. Fig. 12 is a detail view of the lock 64 and its parts, and 55 Fig. 13 is a section on line x—x of Fig. 12.

With the present invention the use of electric motors or other such devices for moving the signal means, which latter may be typified by an ordinary semaphore, is 60 avoided and the action of gravity is relied upon as not only more certain in operation but also as avoiding the use of large amounts of copper in the form of conductors, thereby very materially reducing the cost of installation and repair.

In Figs. 7, 8 and 10 traffic rails 1 are indicated and only a single track is shown, this being sufficient for the purposes of the present invention, but it will be understood that 70 the invention is equally well adapted for double track railways. Alongside one of the traffic rails 1 in position to be engaged by the wheels of the train is a pivoted bar 2 which when engaged by the wheels of the 75 train will be depressed to the level of the tread of the track. Alongside the track adjacent the free end of the bar 2 is a box 3 entered by a rod 4 underriding the free end of the bar 2. Within the box 3 is a rock shaft 6 having arms 7, 8 disposed at substantially right angles so that the shaft and arms become in effect a bell crank lever. Extending from the box 3 is a pipe or conduit 9 leading to another box 10 surmounted by a 80 casing 11 from which latter rises a mast or post 12 carrying at its upper end a semaphore arm 13 designed to constitute a visible block signal. The arm 8 is connected by a strand 14, which may be a flexible steel rope, 85 to mechanism designed to operate the semaphore arm 13. The strand 14 is passed through the pipe 9 and around a direction changing idler pulley 15 within the box 10 and thence upward into the casing 11 where it is attached to mechanism to be described. The same mechanism is connected by a rod 16 to the semaphore arm 13 so that under 90 certain conditions the semaphore arm 13 will stand horizontally or at danger and under 95 other conditions will be pendant or upright in accordance with the desired position of safety.

An example of the semaphore operating mechanism which may be used in connection 100 with the present invention is illustrated in

Figs. 1 to 5 both inclusive, this mechanism being confined within the casing 11, but in the said figures the casing is omitted. There is a frame 17 of suitable shape having bearings in which a bar 18 may slide in the direction of its length, the direction of movement being ordinarily vertical. The bar 18 constitutes the lower end of the rod 16 of Figs. 8 and 9 connected to the semaphore arm 13 so that when the bar 18 and rod 16 move upwardly the semaphore arm will be moved to the danger or horizontal position and when the bar 18 and rod 16 move downwardly the semaphore will be moved 15 to the safety position, the construction being such that the semaphore arm 13 will move either to the upright or pendent position, as desired, this being determined by connecting the rod 16 to one side or the other of the 20 pivot of the semaphore arm 13, as shown in Fig. 11. The lower end of the bar 18 is weighted as indicated at 19 and at an intermediate point the bar is provided with rack teeth 20.

25 Fast on the frame 1 is a bracket 21 from which projects a pin 22 forming the journal for a lever 23 having one end in the shape of a segmental gear 24 meshing with the rack 20. The other end of the lever carries 30 a roller 25. Slidably mounted in the frame 1 on the side thereof remote from the bar 18 but capable of moving in parallel relation thereto is another bar 26 carrying at a point to be underridden by the roller 25 a bracket 35 27 and at an intermediate point formed with a shoulder 28. Mounted in the frame 1 in position to engage the shoulder 28 when the bar 26 is in the lowermost position is a 40 slidable latch member 29 terminating at its active end in a roller 30 adapted to over-ride the shoulder 28 when the bar 26 is lowered and to move along one edge of the bar when the latter is elevated. The latch member 29 is mounted in a block 31 fast in the frame 45 50 and is under the control of a latch lever 32 having one end engaging the latch 29 and the other connected by a link 33 to the core 34 of a solenoid 36 suitably supported in the frame 1. The structure is such that when the solenoid 36 is energized the core 34 is drawn thereinto and through the link 33 and lever 32 causes a longitudinal movement of the latch 29 in a direction away from the bar 26, but when the solenoid 36 is deenergized then the weight of the parts will cause 55 a movement of the latch 29 toward the bar 26 and when the bar is depressed the range of movement is sufficient to cause the end 30 of the bar 29 to over-ride the shoulder 28 60 thus locking the bar 26 in the lowered position. The lower end of the bar 26 straddles and is pivoted to a lever 37 having at its free end a weight 38 tending at all times to lower the bar 26. The lever 37 is forced upwardly 65 so as to elevate the bar 26 by means of a

spring 39 surrounding a rod 40 which at its upper end is formed with a cap 41 or such cap is made fast thereto and fast on or formed on the cap 41 is a stem 42 under-riding the lever 37. The rope 14 at the end 70 remote from the bell crank lever in the box 3 is made fast to the rod 40. Mounted on the frame 1 is the cylinder 43 of a dash pot, this cylinder inclosing a piston 44 and to this piston there is connected a piston rod 45 which at the end remote from the piston 44 is connected by a bracket 46 to the bar 26. The dash pot cylinder 43 is provided with a relief cock 47 by means of which the action 75 of the dash pot may be controlled at will. 80

Let it be assumed that a train passes over the bar 2 on the track, the free end of this bar is depressed and acting through the bell crank lever within the casing 3 draws on the rope 14 in a direction to move the rod 40 and its head 41 against the action of the spring 39 and away from the lever 37. The weight 38 on the lever 37 at once becomes active to cause a movement of the bar 26 in a downward direction and this action 90 continues until the latch 29 rides over the shoulder 28 and the bar 26 thereby becomes locked in the lowered position. This downward movement of the bar 26 under the action of the weight 38 is sufficiently forceful 95 to overcome the weight 19 of the bar 18 and the parts controlled by the bar 18 so that the lever 23 rests on its pivot support and the bar 18 is lifted by the gear segment 24 engaging the rack 20, the movement being sufficient to carry the semaphore arm 13 from the safety position to the danger position, and this position is automatically maintained until the solenoid 36 is energized thereby attracting the core 34 and through 100 the link 33 and lever 32 moving the latch 29 so that its end 30 escapes from the shoulder 28 when the action of the spring 39 will neutralize the weight 38 and the weight 19 will then carry the bar 18 downward thus again setting the semaphore arm 13 at safety and through the gear segment 24 and lever 23 acting on the bracket 27 will cause the upward movement of the bar 26 to its normal position, the spring 39 and weights 38 115 and 19 being properly proportioned for this action. 110

In order to provide for certain contingencies which may arise in practice there are other solenoids 48, 49, respectively carried by the frame 17. The solenoid 48 is provided with a core 50 connected by a link 51 to one end of a bell crank lever 52, the other end of which controls a slidable latch member 53 mounted on the frame 1, this latch member being urged in one direction by a lever 54 carrying a weight 55, such construction being preferred to the use of a spring for the same purpose. Mounted to 120 slide on the frame 17 is another bar 56 125

formed with a shoulder or lug 57 in the path of the latch member 53. This bar also carries a pin 58 in the path of the bracket 59 on the bar 26. The bar 56 is operatively connected to one end of a rock lever 60 mounted on the frame and the other end of this lever is operatively connected to another slideable bar 61 parallel to the bar 18. The bar 61 carries a shoulder or projection 62 and the bar 18 carries a slideable latch member 63 movable into and out of the path of the shoulder 62. This latch member is provided with a pin 64 designed to engage a ledge 65 on the corresponding portion of the frame 1, this ledge being formed with an inclined portion 66 so positioned that when the bar 18 is in the elevated position the latch member 63 will be impelled by the inclined portion 66 of the ledge 65 toward the shoulder 62. Adjacent the inclined portion 66 is a gate 67 designed to engage the pin 64 on the return movement of the bar 18 and hold the latch member 63 over the shoulder or projection 62 so that it may not be retracted from such position while the bar 18 is traveling along the gate 67. A spring 68 carried by the bar 18 tends to move the latch member 63 to the retracted position and so moves it when the pin 64 escapes from the gate 67, the pin 64 engaging the ledge 65 when the latch member 63 has been moved under the action of the spring 68. The solenoid 49 is provided with an armature or core 69 acting on a lever 70 on the frame 1, this lever normally engaging a lug or projection 71 on the bar 61.

The traffic rails 1 are electrically continuous for block lengths but are insulated one from the other and the tracks of one block are insulated from the tracks of the next adjacent blocks. Lodged within the casing 11 is a relay 72. This relay is provided with an armature 73 carried by a stem or rod 74 suitably guided in the frame of the relay, the armature 73 being also guided by pins 75 projecting axially from the cores of the magnets of the relays. The ends of the rod 74 carry contact members 76 and 77 respectively, and in the path of these contact members are other contact members 78, 79 respectively. Thus it will be seen that the two longer bars 18 and 26, are operably connected by means of the segment 24 and bracket 27 so that the movement of either bar in one direction will impart to the other bar movement in the opposite direction; and further that the pair of short bars 61 and 56, are disposed adjacent to the respective bars 18 and 26, so that the movement of the bar 18 downwardly by gravity, will cause its lock or latch member 63 to engage the shoulder or projection 62 of the bar 61, pulling the bar 61 downwardly and thus raising the bar 56. A reverse movement of the gravity actuated bar 26 will bring the bracket 59

of bar 26 into engagement with the pin 57 of the bar 56, to pull said bar 56 downwardly and consequently raise the bar 61. By this means the coaction of the various bars is readily seen, and as before brought out the locking devices and releasing devices therefor will permit the operation just described.

The magnets of the relay 72 are connected by conductors 80, 81 respectively to the two rails 1 of the track of the block section controlled by the structure of the present invention, these conductors 80 and 81 being connected to one end of the rails 1 while the other ends of the rails 1 are connected by conductors 82, 83 to the opposite sides of a battery 84 or other source of electric current. Since it is the design of the invention that the battery 84 should normally charge the magnets of the relay 72 connected to the same rails as the battery, it is preferred that the battery 84 be of the type known as a gravity battery, since such batteries operate advantageously on closed circuits. So long as the relay magnets are charged the armature 73 is attracted and the contacts 77 and 78 are maintained closed and the contacts 76 and 79 are separated. When however the magnets of the relay 72 are no longer charged the armature 73 moves away from the magnets and the contacts 76 and 79 are brought into engagement while the contacts 77 and 78 are separated.

At each block station there is a battery 85 which however may be replaced by any other suitable source of current, and ordinarily it is preferred to use an Edison-Lalande battery since such battery stands up well on open circuits, and the demands thereon are but momentary. This battery is connected on one side by a conductor 86 to the armature 73. On the other side the battery 85 is connected by a conductor 87 to one side of the solenoid 49, while the other side of this solenoid is connected by a conductor 88 to a contact terminal 89 in matching relation to another contact terminal 90 connected by a conductor 91 to the terminal 78 of the relay. The contact terminals 89 and 90 are in the path of a bridging piece 92 on the piston 44 of the dash pot 43, although this does not preclude the mounting of the bridging piece 92 on some other moving part of the structure adapted for the purpose. The object of the bridge piece 92 will appear hereinafter. Branched off from one side of the battery, say from the conductor 87 is another conductor 88' leading to a contact terminal 89' having a matching contact terminal 90' and these two contact terminals are in the path of a bridging member 91' carried by any appropriate movable part of the structure, say the bar 61. The contact 90' is connected by a conductor 92' to one side of the solenoid 48 and the other side of this sole-

noid is connected by a conductor 93 to the contact 79. Branched off from the conductor 87 is another conductor 94 leading to a contact terminal 95 having a matching terminal 96 and these two terminals are in the path of a bridging member 97 carried by an appropriate movable part of the structure, say the bar 26. The contact terminal 96 is connected by a conductor 98 to another contact terminal 99 having a matching contact terminal 100 connected by a conductor 101 to one side of the solenoid 49. The contact terminals 99 and 100 are in the path of a bridging piece 102 carried by an appropriate movable part of the structure, say the bar 56. The other side of the solenoid 49 is connected by a conductor 103 to the other side of the battery 85 from that connected to the conductor 87. The normal condition of the parts is diagrammatically represented in Fig. 10 at the right hand end thereof where there is indicated the electrical connections of a block station while at the left hand end of the same figure is a diagram illustrating the electrical connections of an adjacent block section. Let it be assumed that there has already entered upon the block section at the left hand end of Fig. 10 a railway train represented by an axle and wheels at 104 and that the train is traveling toward the right as indicated in said Fig. 10. As soon as the train 104 enters upon the block the rails 1 were bridged by said train so that the battery 84 becomes short-circuited through the train 104 and the current of the battery 84 is no longer effective upon the magnets of the relay 72 so that the armature 73 moves away from the magnets and the contacts 76 and 79 come together while the contacts 77 and 78 are separated. As the train entered the block the wheels of the engine come into contact with the bar 2 and the free end of the latter was depressed thus acting through the rock lever within the box 2 to turn the same in a direction to move the cable or rope 14. This results in compressing the spring 39 so that the uplifting force of the spring is neutralized and the weight 38 therefore causes the lever 37 to move in a direction to pull the bar 26 downwardly, this movement being resisted by the dash pot 43 to the desired extent so that the parts do not move too suddenly. The downward movement of the bar 26 continues until the latch 29 over-rides the shoulder 28, thus locking the bar in the depressed position. The downward movement of the bar 26 has caused a rocking of the lever 23 in a direction to raise the bar 18 through the intermediary of the gear 24 and rack 20, this resulting in the movement of the semaphore arm 13 to the danger position where it remains locked because of the over-riding relation of the latch 29 to the shoulder 28. As

the train 104 entered on the block and so caused the deenergization of the solenoid 72 there was established a circuit from the battery 85 through the conductor 86 to the armature 73, thence by the contacts 76 and 79 now closed to the conductor 93, thence through the solenoid 48 and by way of the conductor 92 to the contact terminal 90'. This terminal is at this time connected to the terminal 89' by the bridging piece 91', the bar 61 being in the lowered position since the train has not yet engaged the bar 2 to cause the operation of the semaphore in the manner just described. The circuit from the contact 89' is completed by way of the conductor 88' to the conductor 87 and thence back to the battery 85. The solenoid 48 is therefore energized and the latch 53 is withdrawn from beneath the shoulder or ledge 57 so that when the bar 26 moves downwardly the bracket 59 will engage the pin 58 and cause a downward movement of the bar 56 and a corresponding upward movement of the bar 61 which immediately breaks the circuit to the solenoid 48 because the bar 61 carries the bridging piece 91 away from the contact terminals 89' and 90'. The battery 85 is therefore in service but a very short time but sufficiently long to unlatch the bar 56 and permit its movement beyond the locking position of the latch 53, the latter being moved toward its normal position by the weight 55 as soon as the solenoid 48 becomes deenergized.

Should from some cause or other the bar 26 be moved downwardly without the solenoid 48 being energized its further movement would be arrested by the engagement of the bracket 59 with the pin 58 and the semaphore would not be carried to the danger position, the bar 26 immediately returning to the first position as soon as the cause of this movement ceases, since the movement is insufficient to lock the bar 26. Assuming that in the normal operation of the parts the bar 18 is raised by the lowering movement of the bar 26 and the bar 61 is raised by the lowering movement of the bar 56, the upward movement of the bar 61 carries the block or shoulder 62 to the upper position and at the same time the latch 63 is carried by the bar 18 upwardly until ultimately the inclined portion 66 of the ledge 65 is reached and this causes a projection of the latch 63 over the block or shoulder 62 thus locking the bar 18 to the bar 61, the gate 67 preventing the return movement of the latch 63 when finally the bar 18 is moved downwardly.

The circuit through the solenoid 49 is controlled by the bridging pieces 97 and 102 carried by the bar 26 and bar 56 respectively. Under normal inactive conditions the bridging piece 97 connects the contacts 95 and 96, but the bridging piece 102 is moved away

from the contacts 99 and 100, and when the parts are operated in the manner described, the bridging piece 97 is moved away from the contacts 95 and 96 and the bridging 5 piece 102 is moved into engagement with the contacts 99 and 100. Should however the bar 56 fail to return to its normal position when the bar 26 moves to its normal position the circuit through the solenoid 49 is completed and the said solenoid becomes 10 active. Then the armature 69 and the solenoid 49 are attracted and acting through the lever 70 will move the bar 61 toward its normal position, thus elevating the bar 56 15 and the solenoid 49 is again deenergized by the breaking of the circuit at the contacts 99 and 100. The solenoids 48 and 49 are in the nature of emergency solenoids to correct ineffective operations of the system.

20 As soon as the train 104 passes from the block section under consideration onto the next section of track the battery 84 is no longer short circuited and becomes active to the relay 72 energizing the magnets thereof 25 and causing the attraction of the armature 73 which brings the contacts 77 and 78 into engagement and thereby establishes a circuit from the battery 85 by way of the conductor 86 to the armature 73 thence by the stem 74 30 to the contacts 77 and 78, thence by way of the conductor 91 to the contact terminals 89 and 90 then bridged by the bridging piece 92, thence by the conductor 88 to the solenoid 36 and returning to the battery by 35 way of conductor 87. This causes the energization of the solenoid 36 and the core 34 is drawn thereinto acting through the link 33 and lever 32 on the latch 29 to withdraw the end 30 thereof from overriding relation 40 to the shoulder 28. The bar 26 being now unlocked responds to the expansive action of the spring 39 and moves upwardly, thus causing the downward movement of the bar 18 aided by the weight 19. The downward 45 movement of the bar 18 acts through the latch 63 on the bar 61 and causes the latter to also move downwardly, thus raising the bar 56 to the normal position where the latch 53 under-rides the projection or shoulder 57 50 thus locking the bar 56 in the elevated position. As soon as the latch 63 reaches the lower end of the gate 67 the pin 64 escapes from the gate and the latch is moved to the retracted position by the spring 68 so that 55 the pin 64 again rests against the ledge 65. The up and down movements of the bars 26 and 18 are controlled by the dash pot 43 so that these movements may be as fast or slow as desired.

60 It will be observed that the only conductors other than the traffic rails are the short lengths at the block stations and that long lines of expensive copper conductors are completely obviated, since the operation 65 of the device is largely due to the action of

gravity and no electric motors necessitating extended operating circuits are needed.

What is claimed is:

1. A railway block signal system, including a visual signal, two slidable bars, connecting mechanism for both bars, whereby movement of one bar in one direction will cause the movement of the other bar in an opposite direction, one of said bars being connected to the signal, an overbalancing 70 means for the bars and signal connected to the bar attached to the signal and to normally hold the signal at safety, train controlled means at the entrance to the block for actuating the other bar to operate the signal 75 bar in opposition to the overbalancing means and to display the signal at danger, a lock for holding the bars against the action of the overbalancing means, and train controlled means, actuated due to the exit of 80 the train from the block, for releasing the bars and the signal whereby they are subject to the overbalancing means.

2. A railway block signal system, including a visual signal, two slidable bars, connecting mechanism for both bars, whereby movement of one bar in one direction will cause the movement of the other bar in an opposite direction, one of said bars being connected to the signal, a weight connected 90 to the bar attached to the signal to normally hold the signal at safety, train controlled means at the entrance of the block for actuating the other bar for operating the signal bar in opposition to the weight and 95 to display the signal at danger, a lock for holding the bars against the action of the weight, and train controlled means, actuated due to the exit of the train from the block, 100 for releasing the bars and the signal whereby they are subject to the action of the weight.

3. A railway block signal system, including a visual signal, two slidable bars, means connecting both bars, whereby movement of one bar in one direction will cause the movement of the other bar in an opposite direction, one of said bars being connected to the signal, an overbalancing means for the bars and signal connected to the bar attached to the signal to normally hold the signal in one position, train controlled means at the entrance of the block for actuating the other bar for operating the signal in 110 opposition to the overbalancing means and to display the signal in the other position, a lock for holding the bars against the overbalancing means, and train controlled means, actuated due to the exit of the train 115 from the block, for releasing the bars and the signal whereby they are subject to the overbalancing means.

4. A railway block signal system, including a visual signal, two slidable bars, means connecting both bars, whereby movement of 120

one bar in one direction will cause movement of the other in an opposite direction, one of said bars being connected to the signal, a weight connected to the bar attached to the 5 signal to normally hold the signal in one position, train controlled means at the entrance of the block for actuating the other bar for operating the signal bar in opposition to the weight and to display the signal 10 in the other position, a lock for holding the bars against the action of the weight, and train controlled means, actuated due to the exit of the train from the block for releasing the bar and the signal whereby they are 15 subject to the action of the weight.

5. In a railway block signal system for railways, a closed electrical circuit including a source of electrical energy, the traffic rails and a primary electric motor; a secondary 20 circuit including a source of electrical energy and two switches; a visual signal; two slidable bars; connecting mechanism for both bars, whereby movement of one bar in one direction will cause the movement of the 25 other bar in an opposite direction, one of said bars being connected to the signal; an overbalancing means for the bars and the signal connected to the bar attached to the signal to normally hold the signal at safety; 30 means controlled by one of the bars for closing one of the switches of the secondary circuit when the bars are operated against the overbalancing means; an automatic lock for holding the bars against the overbalancing 35 means when said switch is closed; an electrical control for the lock disposed in the secondary circuit; train controlled means at the entrance of the block for moving the members against the overbalancing means 40 and into locked position with one switch closed, the short circuiting of the rails by the train causing the deenergization of the primary electric motor, while the passage of the train out of the block and the consequent 45 energization of said primary electric motor closes the second switch of the secondary circuit to energize said circuit and elec-

trically actuate the automatic lock to release the bars whereby they are moved by the overbalance and the first switch is 50 simultaneously opened.

6. In a railway block signal system for railways, a closed electrical circuit including a source of electrical energy, the traffic rails and a primary electric motor; a secondary 55 circuit including a source of electrical energy and two switches; a visual signal; two slidable bars; connecting mechanism for both bars, whereby movement of one bar in one direction will cause the movement of the 60 other bar in an opposite direction, one of said bars being connected to the signal; a weight connected to the signal carrying bar to normally hold the signal at safety; means controlled by one of the bars for closing one 65 of the switches of the secondary circuit when the bars are operated in opposition to the weight; an automatic lock for holding the bars against the action of the weight when said switch is closed; an electrical control 70 for the lock disposed in the secondary circuit; train controlled means at the entrance of the block for moving the members against the action of the weight and into locked 75 position with one switch closed; an electrical control for the lock disposed in the secondary circuit; the short circuiting of the rails by the train causing the deenergization of the primary electric motor while the passage of the train out of the block and the consequent 80 energization of said primary electric motor closes the second switch of the secondary circuit to energize the said circuit and electrically actuate the automatic lock to release the bars whereby they are 85 moved by the weight and the first switch is simultaneously opened.

In testimony that I claim the foregoing as my own, I have hereto affixed my signature in the presence of two witnesses.

ROBERT F. HUDSON.

Witnesses:

EDWARD L. RYAN,
L. L. KELLEY.
